Design for Plates of the Parlor Stove "Reflector",
A. G. Fidder & Wm. L. Gundersen, of Troy, N. Y.;
and to George Warren, of Mechanicville, Saratoga Co., N. Y.

Patented Jan'y 12 1858.

Dec. 984

N. S. Vedder & Wm. L. Sanderson of Troy, N.Y.

Assignors to —
George Warren of Mechanicville N.Y.
Letters Patent No. 984 - dated Jan: 12th 1858.

~~~~~  
The schedule referred to in these Letters Patent & making part of the same.

~~~~~  
To all whom it may concern:

Be it known that we N. S. Vedder and
Wm. L. Sanderson, each of the city of Troy, in the county of Rensselaer
and State of New York, have jointly invented or produced a new &
original design for the upper and lower side plates of a Parlor Stove,

called the "Reflector"; and we do hereby declare that the following is a full and exact description thereof, reference being had to the annexed photographic drawings making a part of this specification, in which

Fig. 1 represents a side-plate of the upper section of the stove, and,

Fig. 2, a side-plate of the lower section thereof.

Our ornamental design for the upper side-plate consists of the concentric circular scroll-leaf wreaths A. and B. of the particular character shown, separated by the ring of check-work ground C.— Our design for the lower side-plate consists of the large compound ornament shown thereon in Fig. 2; consisting of the shell D. top-piece E. inner leaves F. F. and the outer stems-of-scroll-leaves G. G.

That we claim as our invention or production and desire to secure by Letters Patent is the ornamental design herein described and represented in the annexed drawings for the upper & side for the lower side plates of a Parlor Stove.
